UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

DESIGN FOR A LANTERN-REFLECTOR.

SPECIFICATION forming part of Design No. 31,587, dated October 3, 1899.

Application filed September 5, 1899. Serial No. 729,564. Term of patent 14 years.

To all whom it may concern:

Be it known that I, FRANK RHIND, a citizen
of the United States, residing at Bridgeport,
Connecticut, have invented and produced a
new and original Design for a Lantern-Reflec-
t⁵tor, of which the following is a specifica-
tion.

In the accompanying drawings, Figures I
and II are respectively side and front eleva-
t^oions of a lantern-reflector, showing my de-
sign.

1 designates a cup-shaped reflector body
portion provided with a cylindric portion 2
at its smaller end and at its larger open end
5 with a diagonally-truncated substantially cy-

lindric portion 3, the free edge of which is
finished with a bead 4.

The leading feature of my design is the cup-
shaped portion formed with a cylindric por-
tion of reduced diameter at its smaller end ²⁰
and with a diagonally-truncated cylindric
portion at its larger end.

What I claim is—

The design for a lantern-reflector herein de-
scribed and shown.

FRANK RHIND.
